UNITED STATES PATENT OFFICE.

JOHN VAN, OF CINCINNATI, OHIO.

IMPROVEMENT IN TOP-PLATES FOR COOKING-STOVES.

Specification forming part of Letters Patent No. **141,838**, dated August 12, 1873; application filed June 14, 1873.

To all whom it may concern:

Be it known that I, JOHN VAN, of Cincinnati, Ohio, have invented an Improved Top-Plate for Stoves and Ranges, of which the following is a specification:

My invention is designed to prevent the warping of the top-plate of a stove or range, and particularly of that portion which is situated immediately over the fire. For this purpose I form in one piece or casting with said plate a duct or hollow rib, so located on the under side of said plate as to stiffen those parts most liable to sag or warp, and at the same time to conduct smoke, &c., from the cooler portions near the sides of the fire-space and deliver them into the hotter portions so as to maintain a nearly equal temperature at all parts of the plate. This duct or hollow rib being, with its openings, wholly on the under side of the plate, and cast solidly thereto, is invisible from above, and is not liable to have its inlets choked with matter falling upon the stove, nor obstructed by pots or other objects placed upon the top thereof.

Figures 1 and 2 are under-side views of two forms of top-plates of a cooking-range with my improvement. Figs. 3 and 4 are sections in the lines *x x* and *y y*, respectively.

A represents the top-plate proper. B is a duct, tunnel-way, or hollow rib, cast to the

under surface of said plate, and having its openings wholly at the ends of the rib and on said under side of the plate, and so located as to communicate at their inlets or receiving-ends with those portions of the fire-space near the sides of the stove, and consequently with the comparatively cool portions of said space and at their outlets with the hotter central portions of said space, so as to insure constant passage of the cooler gases in the direction indicated by arrows, by maintenance of a nearly equal temperature at all parts of the plate, which, in conjunction with the stiffening effect of the said hollow rib, effectually prevents any warp or sag of the plate.

I claim as new and of my invention—

A top-plate for a stove or range, having cast solidly to its under side the hollow stiffening piece or rib B having one or more inlets in the cooler portion of the fire-space and one or more outlets in the hotter portion of the same, substantially as and for the purpose set forth.

In testimony of which invention I hereunto set my hand.

JOHN VAN.
